UNITED STATES PATENT OFFICE.

WILLIAM S. HAMM, OF HUBBARD WOODS, AND JAMES A. GIESE, OF CHICAGO, ILLINOIS,
ASSIGNORS TO THE ADAMS & WESTLAKE COMPANY, A CORPORATION OF
ILLINOIS.

DOOR LATCH.

Application filed September 4, 1920. Serial No. 408,304.

To all whom it may concern:

Be it known that we, WILLIAM S. HAMM and JAMES A. GIESE, citizens of the United States, and residents of Hubbard Woods, 5 county of Cook, State of Illinois, and Chicago, county of Cook, and State of Illinois, respectively, have invented certain new and useful Improvements in Door Latches, of which the following is a specification, and 10 which are illustrated in the accompanying drawings, forming a part thereof.

The invention relates to latches of the mortise type, in which the latch casing is entered into an aperture in the edge of the 15 door, the latch being controlled by a spindle extending through the door and provided with suitable knobs or handles.

The object of the invention is to provide improved means for assembling the various 20 parts of the latch mechanism with the door and securely holding such parts in place.

An embodiment of the invention is hereinafter described, and is illustrated in the accompanying drawings, in which

25 Fig. 1 is a detail edge elevation of the door with the latch applied thereto;

Fig. 2 is a similar view of a side face of the door;

Fig. 3 is a detail section on the line 3—3 30 of Fig. 2;

Fig. 4 is a detail section on the line 4—4 of Fig. 2;

Fig. 5 is a detail section on the line 5—5 35 of Fig. 1;

Fig. 6 is a view in perspective of the inner 40 face of the escutcheon plate forming a part of the latch mechanism;

Figs. 7 and 8 are views similar to Figs. 1 and 2, showing a modified form of construction;

Fig. 9 is a sectional view on the line 9—9 45 of Fig. 8;

Fig. 10 is a sectional view on the line 10—10 of Fig. 9;

Fig. 11 is a view similar to Fig. 8, showing 50 another modification;

Fig. 12 is a sectional view on the line 12—12 of Fig. 11, and

Fig. 13 is a view in perspective of the 55 latch casing shown in Figs. 7 to 10.

The latch is illustrated in connection with a hollow metal door, 10, though is capable of being applied to doors of other forms and material.

The latch casing is shown at 11, and is 55 seated within the chamber of the door 10, being entered thereinto through an aperture in the edge wall 12 of the door, which aperture the front face of the casing completely fills, such face being flush with the door edge 12 60 when the parts are assembled. The latching element or dog 13 is shown as of the oscillating type, and as being pivoted at 14 to the casing 11. This feature, and the mechanism for controlling the dog, are, however, not of the essence of the invention, and are therefore not fully shown. When the latch casing is inserted into the door one 65 of its side faces bears against the inner surface of one of the side walls of the door, as 70 shown in Fig. 3, a lug, or pair of lugs, 15 being provided at the inner end and opposite side of the latch casing to bear against the inner surface of the opposite side wall 75 of the door.

A pair of escutcheon plates 16, 17, are applied one to each of the side faces of the door, and through them and the latch casing extends a spindle 18 by means of which the dog 13 is controlled, the spindle entering 80 into a pair of handles 19, 20, of any desired form and which are connected with the escutcheon plates in the usual manner.

One of the escutcheon plates, as 16, is provided on its inner surface with a pair of instanding ribs or flanges 21, which project into the interior of the door, the side wall of which is suitably apertured for their reception, these ribs being spaced to slidingly receive the latch casing as the latter is inserted into the door. This escutcheon plate is also provided with an instanding stud 22, against which the inner end of the latch casing, or preferably a rearwardly extending boss 23 formed thereon, abuts when the latch casing is properly positioned within the door.

The stud 22 is preferably provided at its inner end with a forwardly projecting lip 24, which overlaps the boss 23, thereby securing the escutcheon plate against removal while the latch casing is in service position. In lieu of the lip 24 the ribs 21 may be longitudinally undercut, the edges of the latch casing being correspondingly configured to 105 receive them, as shown in Fig. 4.

The two escutcheon plates are secured to the door by means of screws, as 25, four be-

ing shown, and preferably these screws enter instanding posts, as 26, 27, formed integral with the two escutcheon plates and mating together in the well known and long practiced manner.

In assembling the latch mechanism in connection with a door, the escutcheon plate 16 is first positioned, and the latch casing 11 is then inserted and entered between the ribs 21, its inner end abutting against the stud 22, its boss 23, when present, interfitting under the lip 24. This interengagement of the latch casing and escutcheon plate temporarily holds such parts in position, and thereupon the spindle 18 is inserted and the opposite escutcheon plate 17 is applied and the screws 25 driven home, thus completing the operation. The spindle 18 prevents longitudinal movement of the latch casing and lateral movement thereof in either direction is prevented both by the spindle and by the engagement of the casing with the walls of the door, and with the ribs 21.

While a preferred form of construction has been shown and described, the invention may be variously embodied. For example, the length of the ribs 21 is immaterial and they may be so shortened as to be mere posts.

In Figs. 7 to 10 and 13 a construction is shown in which the supporting of the latch casing and the interlocking therewith of one of the escutcheon plates are provided by a single rib 28 on the plate and a channel 29 in the back face of the casing. By limiting the length of the channel a stop is provided for preventing the casing from entering too far within the door. The rib and channel are so configured in cross section as to secure a dovetail, or T engagement.

In the construction of Figs. 1 to 6 a single rib 24, located below the casing will serve to support it, but the two ribs are preferred to relieve the actuating spindle in part of the duty of retaining the casing from displacement by jars.

In Figs. 11 and 12 a form of construction is shown in which the latch is supported by the posts through which the securing screws 25 are entered. In order that they may serve the additional function such posts here designated by the numeral 30 are positioned farther from the margins of the escutcheon plates. They may be provided with lateral grooves 31 to receive the latch casing to pro-

vide for the interlocking of the latter with one of the plates. A post, as 32, limits the inward movement of the casing.

We claim as our invention—

1. In combination, a door latch casing adapted to enter a recess in the door edge, and a plate for attachment to the side face of the door and having instanding ribs spaced to engage opposite margins of the casing. 60

2. In combination, a door latch casing of the mortise type, and an escutcheon plate having a projection underlying and supportingly engaging a part of the casing when the latter is entered into service position. 70

3. In combination, a door, a mortise latch casing in the door, and an escutcheon plate separably interlocked with the casing to prevent the displacement of the escutcheon plate laterally with respect to the door. 75

4. In combination, a mortise latch casing, and an escutcheon plate having an instanding rib upon which the casing is supported.

5. In combination, an escutcheon plate 80 having a pair of instanding horizontal vertically spaced ribs, and a latch casing having dovetail engagement with the ribs.

6. In combination, a mortise latch casing, and an escutcheon plate having an instanding part for supporting the casing and an instanding abutment engaging the inner end of the casing. 85

7. In combination, a mortise latch casing, and an escutcheon plate having an instanding rib interlocking with the casing. 90

8. In combination, a door latch casing adapted to enter a recess in the door edge, and a plate for attachment to the side face of the door and held in place by interengagement with the latch casing. 95

9. In combination, a mortise latch casing adapted for use in connection with a hollow door, and an escutcheon plate having a projection for entering the chamber of the door 100 and upon which the latch casing may slide as entered into service position.

10. In combination, a mortise latch casing adapted for use in connection with a hollow door, and an escutcheon plate adapted to be 105 secured to the side of such door and having a projection extending into the chamber thereof for supporting the latch casing.

WILLIAM S. HAMM.
JAMES A. GIESE.
